Inventor:

Charles Couse,

By Drake & Co Atty's.

UNITED STATES PATENT OFFICE.

CHARLES COUSE, OF BELLEVILLE, NEW JERSEY.

LUBRICATOR.

SPECIFICATION forming part of Letters Patent No. 521,702, dated June 19, 1894.

Application filed February 19, 1894. Serial No. 500,610. (No model.)

To all whom it may concern:

Be it known that I, CHARLES COUSE, a citizen of the United States, residing at Belleville, in the county of Essex and State of New Jersey, have invented certain new and useful Improvements in Lubricators or Automatic Feeds; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to certain improvements in that class of lubricating devices represented by the one shown in my prior Patent No. 508,566, dated November 14, 1893, the objects being to provide a lubricating device that will be adapted for water or feed pipes, through which a very rapid and irregular stream is flowing to reduce the pressure in the oil discharge or passages leading from the reservoir so that the outflow of oil will be more free, and to secure other advantages and results some of which will be referred to hereinafter.

The invention consists in the improved feeding device or lubricator, having the arrangements and combinations of the parts, all substantially as will be hereinafter set forth and finally embraced in the clauses of the claim.

Referring to the accompanying drawings in which like letters of reference indicate corresponding parts in each of the several views, Figure 1 is a central vertical section of the improved feeding or lubricating device, its relation to the feed water pipe being indicated in outline. Fig. 2 is a sectional detail, taken at line *x*. Fig. 3 is an end view of a partitioned or diaphragmed coupling piece, and Fig. 4 is a section of the same taken at line *y*.

In said drawings, *a* indicates the oil chamber or reservoir, which communicates with the feed water pipe, *j*, so as to receive water therefrom. The oil is driven out by the inflowing water to lubricate the water in said feed pipe and the parts—such as a boiler—in connection therewith. Said reservoir *a*, is supplied with a water induction pipe, *b*, adapted to convey the water entering the reservoir to a

point, as at *A*, beneath the oil, *B*. It is also provided with an outlet or feeding projection, *c*, for the oil, extending from the upper part of the reservoir, a valve, *c'*, controlling the outflow through said projection, means, *l*, by which the oil may be supplied to the reservoir, means, *m*, by which the water may be drawn from the reservoir after the latter has been emptied of oil, and a sight tube, *d*, arranged around the projection, *c*, and extending upward therefrom to the oil induction pipe or casting, *i*, and co-operating parts which embody more especially the present invention. These parts are all arranged substantially as shown in my prior patent above referred to.

In my prior construction when the feeding or lubricating apparatus was attached to a feed water pipe through which the water was forced, with more or less irregularity but with great rapidity and force through the feed water pipe, the feeding operations were rendered more or less irregular owing to the eddies and counter currents formed in the branch pipes near their connection with the feed water pipes. By the said prior construction, also, the machine lacked the force necessary to a complete out-feed of the oil therein. These objections are avoided in the improvements which I will now more particularly describe. To the upper side of the reservoir is arranged in connection with the water induction pipe, *b*, within the reservoir and the sight tube, *d*, above the same, a casting, *i*, arranged horizontally so as to allow an outflow of oil and an inflow of water, the latter serving to take the place of the oil in the reservoir and the oil, by gravity, or lack of gravity, and its want of affinity for the water, floating outward over said water to a chambered coupling, *h*. Said horizontal casting, *i*, has, near one extremity means, *i'*, to receive the sight tube, *d*, and form an impervious joint therewith, a plug, *z*, in line with said sight tube, on the opposite side of said casting, for allowing access to said tube and the feeding projection therein, and near the center, said horizontal casting has a transverse water way, *e'*, adapted to form a vertical continuation of the induction tube, *b*, said casting being provided with a lower tubular branch, *e''*, connecting with the top of the reservoir and an upper nipple,

e^2 , to which is coupled a vertical branch, e^3 , through which water is supplied from the branch induction pipe, g , connecting with the coupling h . By means of the vertical pipes, 5 e , e^3 , a hydrostatic column of increased length is secured and thus an increase of pressure on the oil within the reservoir is obtained. The connecting tube, g , is curved upward to admit of the insertion of the branch, e^3 , and 10 a valve, f , is inserted at the joint to enable communication to the reservoir to be cut off when refilling said reservoir with oil. A valve, k , shown in Fig. 2 more clearly, serves to cut off communication through the oil exit 15 passage, e^4 . The ends of the branch induction pipe, g , and horizontal casting, i , are coupled together to give unity and strength to the apparatus, the single coupling piece serving to connect the two parts in one operation 20 to the feed water pipe. Said coupling, h , is provided, interiorly with an inclined partition, h^8 , forming chambers, h^1 , h^2 , which respectively receive the parts, g , i , the said partition separating the entrances of said parts, 25 g , i , as indicated in Figs. 3 and 4. An end piece or plate, o , closes the end of the coupling extending into the feed water pipe, j ; said plate being slotted to receive a projecting end of the partition, which latter may 30 serve as a rivet to hold said plate in place. Said end plate is provided with inlet and outlet perforations, h^4 , h^5 , h^6 , which are comparatively small and lie distant from the pipes g and i so that no eddies may be formed 35 to counteract the actions therein.

The perforation, h^4 , is an oil exit which lies considerably above and away from the pipe, i , and water inlet perforation, h^5 , so that there will be no interference of the outflow of oil. 40 The perforation, h^5 , is a small one, and is only intended to keep a supply of water in the sight tube and the horizontal pipe, i . The perforation, h^6 , serves to provide a way 45 for the water into the chamber h .

It will be evident, that by interposing enlarged chambers between pipes g and i and the feed water pipe in the manner described, the disturbances produced by the rapid flow of water through the said feed water pipe 50 will not be transmitted to the pipe, i , so as to interrupt a steady outflow of oil.

Having thus described the invention, what I claim as new is—

1. In an automatic feeding device for oil, &c., the combination with the reservoir and means for feeding the oil or liquid therefrom in small quantities regularly, into a sight tube, said sight tube, a horizontal tube connecting with said sight tube, supplying water thereto and receiving oil therefrom, and a feed water pipe, of an enlarged chamber, interposed between the end of the horizontal tube and said feed water pipe and having a small opening into said feed water pipe, substantially as set forth.
- 65 2. In an automatic feeding device, the combination with the reservoir, sight tube, feed-

ing projection and water induction tube, b , the casting, i , having the horizontal liquid way therethrough connecting with the sight tube, and a vertical way therein crossing the first said way, and connecting with the tube, b , below and forming a hydrostatic column above the same, a branch pipe, g , leading to the top of said column, and a partitioned coupling, h , connecting said parts g and i , all said parts being combined substantially as and for the purposes set forth.

3. The combination with the reservoir a , having the water induction pipe b , feeding projections c and sight tube, d , a horizontal tube or casting, i , connecting with said induction tube and sight tube but having its fluid passage independent of those in said sight tube and water induction pipe and connecting with an enlarged chamber coupling having a small feeding perforation through which the feed water enters said chamber and said enlarged chambered coupling, substantially as set forth.

4. In combination with the reservoir, and pipe or duct, i , for feeding oil therefrom to the feed water pipe, and said feed water pipe, a chamber interposed between said pipe or duct and said feed water pipe for preventing eddies being formed in said duct, i , by the rapid flow of water in said water pipe and pipes or ducts for feeding water to the reservoir substantially as set forth.

5. The combination with the reservoir, a , induction tube, b , sight tube, d , and horizontal pipe, i , leading to the feed water pipe, of a pipe or tube, e^3 , extending above said horizontal pipe and forming a hydrostatic column of water above said tube, b , and a branch pipe g , leading to the top of said column and a partitioned coupling h , adapted to connect said parts to the feed water pipe, substantially as set forth.

6. The combination with an automatic feeding device, the pipes g and i , a coupling h , adapted to be connected to the feed water pipe and having an interior partition or diaphragm extending between the mouths of said pipes, and a plate, o , at the end of said coupling having perforations h^6 , at one side of said partition and h^4 , h^5 , for the outflow of oil and the inflow of water respectively, substantially as set forth.

7. In combination with the reservoir having the induction pipe, feeding projection, and sight tube, of the casting having the horizontal part to lead to the feed water pipe and having means to receive the sight tube and a downward extension, e , to connect with the induction tube, b , also an upward extension, e^2 , to receive the tube, e^3 , a valve, f , a branch pipe, g , a valve, k , and a coupling for attaching said parts to the feed water pipe, all arranged and adapted to operate substantially as set forth.

8. The combination with an automatic lubricating apparatus, of the water induction branch pipe g and oil eduction pipe, i , of a

coupling, *h*, having an interior partition separating the entrances of said pipes to said couplings and a rear plate, *o*, having perforations for the oil and water the oil perforation lying above said water perforation to prevent the oil entering said water perforation.

In testimony that I claim the foregoing I have hereunto set my hand this 3d day of 10 February, 1894.
